UNITED STATES PATENT OFFICE

147,256

DESIGN FOR A VENDIBLE DISPLAY CONTAINER FOR FINGER RINGS

James J. Waldron, Philadelphia, Pa., assignor to
Waldron & Company, Inc., Philadelphia, Pa.,
a corporation of Pennsylvania

Application March 21, 1946, Serial No. 127,747

Term of patent 14 years

(Cl. D80—15)

To all whom it may concern:

Be it known that I, James J. Waldron, a citizen of the United States and residing at Philadelphia, in the county of Philadelphia, Commonwealth of Pennsylvania, have invented a new, original, and ornamental Design for Vendible Display Container for Finger Rings, of which the following is a specification, reference being had to the accompanying drawing, forming part thereof.

Figure 1 is a perspective view of a vendible display container for finger rings, showing my design.

Figure 2 represents a side elevational view of the embodiment of Figure 1.

Figures 3 and 4 are perspective views of the cap and base portions, respectively, of the embodiment of Figures 1 and 2, shown in disassembled position.

I claim:

The ornamental design for a vendible display container for finger rings, as shown.

JAMES J. WALDRON.
